CLAIM

The ornamental design for a shifter center cage for a vehicle as shown and described.

DESCRIPTION

FIG. 1 is a top, right-side, front perspective view showing my new design;

FIG. 2 is a top, right-side, rear perspective view thereof;

FIG. 3 is a top, rear, left-side perspective view thereof;

FIG. 4 is a top, left-side, front perspective view thereof;

FIG. 5 is another top, left-side, front perspective view thereof;

FIG. 6 is another top, right-side, front perspective view

FIG. 7 is another top, right-side, rear perspective view thereof;

FIG. 8 is another top, rear, left-side perspective view thereof;

FIG. 9 is a front view thereof;

FIG. 10 is a rear view thereof;

FIG. 11 is a left-side view thereof;

FIG. 12 is a right-side view thereof;

FIG. 13 is a top plan view thereof;

FIG. 14 is a bottom plan view thereof;

FIG. 15 is a bottom, right-side, front perspective view showing my new design;

FIG. 16 is a bottom, left-side, front perspective view thereof;

FIG. 17 is a bottom, rear, left-side perspective view thereof; and,

FIG. 18 is a bottom, right-side, rear perspective view thereof.

The dash-dash broken lines in the drawings depict portions of the shifter center cage for a vehicle that form no part of the claimed design.
